TURNBUCKLE TOOL

Silvy H. Knowles, Oklahoma City, Okla.

Application November 24, 1943, Serial No. 511,614

1 Claim. (Cl. 81—13)

This invention relates to tools and more particularly to a turnbuckle tool by means of which the threaded screws or eye-bolts of a turnbuckle may be held stationary while the sleeve or barrel is turned to tighten or loosen the turnbuckle.

At the present time it is customary to manipulate a turnbuckle by means of a rod passed through a transverse opening midway the length of the barrel of a turnbuckle and while the barrel can be easily turned in this manner it is difficult to hold the screws stationary and it is often necessary to have one workman hold the screws stationary while another turns the barrel. Therefore it is one object of the invention to provide a tool by means of which the screws 15 may be easily held stationary with one hand while the barrel is turned with the other hand.

Another object of the invention is to provide a device of this character including a bolt-engaging clamp having jaws for gripping both screws 20 and handles having a latch associated with them so that the jaws will be held in gripping engagement with the bolts during turning of the barrel to tighten or loosen the turnbuckle.

The invention is illustrated in the accompanying drawing wherein:

Figure 1 is a side elevation showing the clamp and the collar applied to a turnbuckle.

Figure 2 is an end view of Figure 1.

Figure 3 is a sectional view taken along line 30 3—3 of Figure 1.

This improved turnbuckle tool consists briefly of a clamp 1 for gripping the threaded rods or screws 2 of a turnbuckle. The screws 2 of the turnbuckle may be eye bolts or of any conventional construction and are oppositely threaded so that when the barrel 4 of the turnbuckle is turned the guy wires 5 tightened or loosened according to the direction in which the barrel is turned. In the present illustration the screws 2 are formed with wire-receiving members 6 having wrench engaging portions 7, this form of turnbuckle being particularly adapted for use in airplane construction as the guy wires are not bent and weakened by being passed through eyes of eye bolts and twisted. The formation of the turnbuckle does not form part of the invention as a conventional form of turnbuckle has been illustrated and the improved tool may be used for tightening or loosening upon turnbuckles of other conventional formation.

The clamp 1 consists of U-shaped yokes 8 which fit one within the other and are pivotally connected by pins 9. Each yoke has its arms split from their lower ends to form forks 10, and these forks carry jaws 11 which extend transversely of

the forks. The jaws have their inner faces formed with V-shaped grooves or recesses so that they may firmly grip the portions of the screws 2 disposed between them when the clamp is in use and have flat gripping engagement with the wrench engaging portions 7 of the screws if screws of this type form portions of the turnbuckle.

Bridge portions of the yokes are reinforced by metal strips 12 and the yokes carry handles 13 and 14 having their lower or inner ends formed with tongues 15 by means of which the handles are firmly fixed to the yokes. The handle 13 carries a latch 16 which is pivoted to the handle by a pin 17 and passes through an opening 18 in handle 14 and a spring 19 which has one end connected with an eye 20 carried by handle 13 and its other end connected to the latch near its pivoted end urges the latch upwardly so that the latch will engage the handle at the upper end of the opening 18 and hold the jaws 11 in gripping engagement with the screws 2. By tilting the outer free end of the latch downwardly the handle 14 will be released and the yokes may be turned about their pivots 9 and the screws released. Since the handles are opposite each other they may be grasped in one hand and the jaws applied to the screws, the handles being then pressed towards each other and held with the jaws firmly gripping the screws.

By use of the improved tool the turnbuckle may be tightened by one person holding the handles of the clamp with one hand and manipulating the turnbuckle with his other hand.

Having thus described the invention, what is claimed is:

A turnbuckle tool including a clamp for holding screws of a turnbuckle stationary while the sleeve of the turnbuckle is turned, said clamp comprising U-shaped yokes having their arms pivotally connected together and split from their free ends to form forks, jaws carried by the forks and extending transversely of the arms of said yokes, said jaws having inner side faces formed with V-shaped recesses extending longitudinally thereof for tight gripping engagement with screws of the turnbuckle, handles carried by said yokes midway the width thereof in opposed relation to each other, a latch pivotally carried by one handle and passing through an opening in the other handle, and a spring carried by the first handle and connected with said latch near the pivoted end thereof for swinging the latch into position for latching engagement with the second mentioned handle at the upper end of the opening formed therein.
